UNITED STATES PATENT OFFICE.

JOSEPH S. GREENLEY, OF SAN JOSE, CALIFORNIA.

WINDOW GUIDE.

Application filed April 21, 1921. Serial No. 463,216.

To all whom it may concern:

Be it known that I, JOSEPH S. GREENLEY, a citizen of the United States, and a resident of San Jose, in the county of Santa Clara and State of California, have invented certain new and useful Improvements in Window Guides, of which the following is a specification.

My invention relates particularly to a guide for the sliding windows of automobiles.

In building enclosed tops for automobiles it is customary to provide sliding windows for both sides thereof. These windows are supported upon suitable hangers and must, of course, be spaced and held by guides arranged at their lower edges and upon the body of the automobile. These guides are carefully made to permit the free movement of the sliding windows therein, and consequently when the automobile is in use the continual weaving of the top causes movement of the windows which in nearly all cases develops into an objectionable rattle.

It is the object of my invention to provide a guide so constructed as to automatically engage the window at all times with sufficient pressure to prevent rattling thereof and yet to permit the proper sliding movement thereof. Another object is to provide a guide that can be adjusted from time to time to the pressure required to take up wear due to the continued use of the sliding window.

In the drawing:

Figure 1 is an end view of my improved guide.

Figure 2 is a left side elevation of Figure 1.

Figure 3 is a right side elevation of Figure 1.

Figure 4 is an end view of another form of my invention.

Figure 5 is a left side elevation of the same.

Figure 6 is a right side elevation of the same.

Figure 7 is an end view of another form of my invention.

Figure 8 is an end view of still another form of my invention.

Referring more particularly to the drawing, 1 indicates a suitable casting adapted to be secured to the upper edge of an automobile body 1^a and provided with upwardly and downwardly extending side flanges as at

2 and 3 respectively, and end webs as at 4 and 5 as shown. The upper surface of member 1 is sufficiently wide to receive the bottom edge of a window 6, and the webs 4 and 5 extend a distance beyond said portion 1 and engage a pin 7. Mounted on pin 7 is a plate member 8 having upwardly and downwardly extending flanges 9 and 10 as shown. A bolt and nut 63 11 is shown connecting flanges 3 and 10, and a spring 12 is arranged on said bolt between said flange and exerting an outward pressure thereon.

The result of this construction is, that by 70 adjustment of the bolt and nut the flange 9 may be adjusted with relation to flange 2 so as to bring to bear upon window 6 just the right pressure to permit its proper sliding movement and yet to positively prevent 75 its rattling in the guide.

The device above described is for a single window only. Where a double guide is required for two sliding windows it may be as shown in Figures 4—5 and 6 in which 80 a body portion 13 is shown provided with an upwardly extending central flange 14 and side flanges 15 and 16 pivotally mounted thereon on pins 17—18, each flange having a downwardly extending portion as 19—20 85 respectively. A bolt and nut 21 connects flanges 19—20 and a spring 22 is mounted on the bolt between said flanges and exerts an outward pressure thereon. In this form the two guides are adjusted by a single 90 spring and bolt, each guide of course functioning as described in connection with Figure 1.

If so desired in the double construction, a central depending and fixed flange as 23 95 may be provided and two springs as 24—25 arranged on bolts 26—27 as shown in Figure 7. This permits the accurate adjustment of either guide independently of the other guide. In Figure 8 both sides of the 100 device are resiliently mounted, the fixed flanges 2 and 3 being replaced by a plate 28 mounted on pivot 9.

It is to be understood of course, that while I have herein shown and described 105 certain preferred forms of my invention, changes in form and construction and method of operation may be made within the scope of the appended claims.

I claim:

1. A sliding window guide comprising a body portion adapted to be mounted upon

2 a fixed support, upwardly and downwardly extending fixed flanges on one side thereof, a plate pivotally mounted upon said body portion in opposed relation to said flanges, and means inserted between the lower portion of said plate and said downwardly extending flange for exerting an outward pressure thereon.

2. A sliding window guide comprising a body portion adapted to be mounted upon a fixed support, upwardly and downwardly extending fixed flanges on one side thereof, a plate pivotally mounted upon said body portion in opposed relation to said flanges, and means inserted between the lower portion of said plate and said downwardly extending flange for exerting an outward pressure thereon, and means for limiting the piv-

otal movement of said plate under said pressure.

3. A sliding window guide comprising a body portion adapted to be mounted upon a fixed support, a window engaging flange arranged thereon, a window engaging flange pivotally mounted thereon in opposed relation to said first flange, and resilient means operatively mounted to urge the second mentioned flange toward the first mentioned flange.

4. A sliding window guide comprising a body portion including a window engaging flange, movable means arranged thereon in opposed relation to said flange, and resilient means operatively mounted to urge said movable means toward said flange.

JOSEPH S. GREENLEY.
